UNITED STATES PATENT OFFICE.

THOMAS JAMES LEAHEY, OF ST. JOHN, NEW BRUNSWICK, CANADA.

RAIL-JOINT.

1,259,533.

Specification of Letters Patent. Patented Mar. 19, 1918.

Application filed November 10, 1917. Serial No. 201,369.

To all whom it may concern:

Be it known that I, THOMAS JAMES LEAHEY, a subject of the King of Great Britain, and resident of the town of St. John, Province of New Brunswick, in the Dominion of Canada, have invented certain new and useful Improvements in Rail-Joints, of which the following is the specification.

10 This invention relates to improvements in rail joints and particularly refers to the means whereby tapered split coppers utilized in securing pins passing through angle bars or fish plates are spread during the operation of driving the coppers into position so automatically securing the coppers in position. Heretofore in using split coppers, it has been found essential to manually spread the point after the copper has been positioned.

15 20 and the objects of the present invention are to overcome this drawback and thus save considerable time in assembling or disassembling a rail joint, to permit of the copper spreading device being utilized with the usual angle bars or fish plates at present in use, to provide means for taking up slackness in the pins when necessary, and generally to adapt the several parts to better perform the functions required of them.

25 30 35 With the above and other objects in view the invention consists essentially of the improved construction particularly described and set forth in the following specification and accompanying drawings forming part of the same.

In the drawings:

Figure 1 is a perspective view of a rail joint embodying the present invention.

Fig. 2 is a side elevation of the same.

40 Fig. 3 is a transverse section on the line 3—3 of Fig. 2.

Fig. 4 is a perspective view of the split copper.

Fig. 5 is a perspective view of a washer.

45 Fig. 6 is a perspective view of a plate carrying the copper spreading device.

Like characters of reference refer to like parts in the several figures.

Referring to the drawings, A represents a pair of rails which are abutting to form a rail joint and are secured in operative position by the angle bars 10 located along the lateral faces of the rails.

Orifices 12 are provided in the web of the 50 rails and are designed to register with ori-

fices 11 formed in the angle bars through which orifices pins 13 pass.

Each pin 13 is provided near the point with a cotter hole 14 with which the tapered split copper 15 is adapted to engage, and so 60 that time and labor may be saved in the assembly of the joint I provide means whereby the copper 15 is spread during the operation of driving the same into position and this consists of a plate 16 having an orifice 65 17 therethrough which engages with the pin 13 and in advance of the orifice 17 is a splitting wedge 18 carried by the said plate.

When the copper 15 is being driven through the hole 14 the point of the copper 70 engages with the wedge 18 and is spread thereby. It is also advisable where chattering of the pins 13 takes place that the slackness can be readily taken up by a washer 19 which is designed to engage with the pin 75 20 and is provided with a peripheral recess 20 which engages with the wedge 18 and prevents rotation of the washer.

In the embodiment illustrated it should be noted that the plate 16 is rectangular and 80 fits snugly between the under face of the ball of the rail A and the lower flange of the angle bar 10 so that movement of the plate 16 cannot take place, while the washer 19 is provided with a tongue 21 in which the recess 85 90 20 is formed. This tongue of course may be dispensed with if the wedge 18 is kept sufficiently near to the orifice 17 to permit of an ordinary round washer 19 being used with the peripheral recess.

In assembling the rail joint the plates 10 are positioned and the pins 13 passed through the orifices 11 and 12 whereupon the plates 16 are positioned with the orifice 17 engaging the pins 13 and when required 95 a washer 19 may be placed on any pin 13 in such a manner that the recess 20 engages with the wedge 18.

The copper 15 is now driven into the cotter hole 14 and when the point of the copper engages with the wedge 18 it is spread thereby during the operation of driving the copper and this completes the rail joint.

In taking the joint apart a blow is given to the head of the copper which tends to 105 force or drive the same out of the cotter hole 14 and during this operation the split end of the copper closes and can thus be readily inserted in the cotter hole when reassembling the joint.

Under ordinary circumstances the washer 19 will not be required but should any of the pins 13 be a little long the difference of length is taken care of by the said washer 5 so that the tapered cotter when driven into position will pull the pin tightly against the angle bar and make a solid joint, so that the rails cannot become displaced or go out of alinement.

10 From this description it will be seen that I have invented a securing means for a rail joint which can be advantageously utilized with fish plates and on the joints at present in use, the several parts being of an extremely simple nature, cheap in construction and formed in such a way that by their use a considerable saving of time and labor is accomplished in assembling or disassembling a rail joint.

Copies of this patent may be obtained for five cents each, by addressing the "Commissioner of Patents, Washington, D. C."

As many changes could be made in the 20 above construction and many apparently widely different embodiments of my invention within the scope of the claim, constructed without departing from the spirit or scope thereof, it is intended that all matter 25 contained in the accompanying specification and drawings shall be interpreted as illustrative and not in a limiting sense.

What I claim as my invention is:

In a rail joint, a plate having a wedge 30 thereon, a bolt passing through the plate having a slotted end, a washer having a peripheral recess engaging with the wedge and a split cotter passing through the slot designed to be spread by the wedge. 35

In witness whereof I have hereunto set my hand.

THOMAS JAMES LEAHEY.
